ABSTRACT: A chute used in apparatus for assembling printing type line castings and having an upper end adapted to be connected to the discharge end of a type casting machine and a lower discharge end. A retainer means normally obstructing the passageway of the chute intermediate its length is shiftable out of said passageway. Power actuated means is provided for withdrawing the retainer means from said passageway. Means responsive to the passage of a discharged casting thereacross for actuating the retainer withdrawal means is positioned above and in the path of the casting.

CASTING ASSEMBLY APPARATUS

SUMMARY OF THE INVENTION

This invention relates to an improved chute used in apparatus for assembling printing type line castings and includes an upper end adapted to be connected to the discharge end of a type casting machine and a lower discharge end for delivering type castings in properly timed relation to a conveyor for transport thereof to an assembly table. A retainer means normally obstructing the passageway of the chute intermediate its length is shiftable out of said passageway. Power actuated means is provided for withdrawing the retainer means from the passageway. Means responsive to the passage of discharged castings thereacross for actuating the retainer withdrawal means is positioned in the path of the casting.

This invention is an improvement upon the printing line casting assembly apparatus described in the Troeger and Fermi application, Ser. No. 708,093, filed Feb. 26, 1968 and commonly owned. During operation of such apparatus, a casting, upon being discharged from a type casting machine, slides down a chute where it is deposited in an upright position upon a receiving and transporting means, such as a conveyor, which carries it to an assembly table, there to be properly assembled into a printing column. During use of such assembly apparatus it has been found that type castings would pitch over and misposition themselves upon the receiving and transporting means at the discharge end of the chute. Upon investigation, it was found that the type castings were attaining too great a speed during their passage down the chute, and that the inertia of the castings tended to cause them to tumble or to pitch over as their leading edge contacted the receiving and transporting means which travels at a slower speed.

Therefore, this invention concerns the introduction of a retainer means correlated to the discharge of a type casting from a type casting machine and shiftable within said chute to momentarily detain or stop the casting at an intermediate position along the chute during its passage down the chute. Upon release of the retainer means the casting resumes its travel in the chute at a speed low enough so that it is discharged onto the receiving and transporting means in a manner to avoid tumbling and pitching thereof on said transporting means.

Accordingly, it is a purpose of this invention to provide an improved apparatus for assembling printing line castings in which a casting as it proceeds down a chute is detained or stopped to insure travel thereof at a low speed when discharged from the chute.

A further object is to provide an inclined chute having retainer means inserted into said chute intermediate its length, means for withdrawing said retainer means, and means positioned above said retainer means responsive to the passage of a casting thereacross for actuating said retainer withdrawal means.

Other objects of this invention will become apparent upon a reading of the invention's description.

BRIEF DESCRIPTION OF THE DRAWINGS

Other objects of this invention will become apparent upon a reading of the invention's description.

BRIEF DESCRIPTION OF THE DRAWING

A preferred embodiment of this invention has been chosen for the purposes of illustration and description wherein:

FIG. 1 is a fragmentary perspective view of the improved apparatus for assembling printing line castings.

FIG. 2 is a cross-sectional view taken along line 2-2 of FIG. 3.

FIG. 3 is a fragmentary detailed longitudinal sectional view taken along line 3-3 of FIG. 1.

FIG. 4 is a circuit diagram for the improved assembly apparatus.

FIG. 5 is the assembly apparatus shown in FIG. 3 in modified form.

DESCRIPTION OF THE PREFERRED EMBODIMENTS

The preferred embodiments illustrated are not intended to be exhaustive or to limit the invention to the precise forms disclosed. They are chosen and described in order to best explain the principles of the invention and its application and practical use to thereby enable others skilled in the art to best utilize the invention.

A downwardly inclined trough or chute 10 is connected at its upper end to the discharge end of a linotype or similar printing line casting machine 12 and is adapted to receive and transport castings discharged from the casting machine. The lower end of chute 10 discharges onto a receiving and transporting means, such as a conveyor 14, which serves to transport the castings between spaced guides 16 to an assembly table (not shown) where the castings are sequentially assembled into printing columns.

Chute 10 includes a bottom member or web 18 and attached side flanges or members 20 and 21 defining a passageway 23. A transverse support plate 22 is secured, as by welding, to the bottom web 18 of chute 10 and has projecting parts 24 and 26 oppositely extending beyond each side of the chute 10. Plate 22 is preferably positioned along the incline of chute 10 proximate to a bend spaced from the chute's junction with conveyor guides 16. An actuating means, such as a solenoid 28, is mounted upon projecting part 24 of plate 22 and has an actuator plunger 30 which extends through an aperture 32 in chute side flange 20 and projects laterally into chute passageway 23 as shown in FIG. 2. A plate 34 is secured to plunger 30 and is positioned between flange 20 of chute 10 and solenoid 28. Plate 34 projects above the adjacent portions of chute flanges 20 and 21.

An anchor bar or pin 38 is secured to projecting part 26 of plate 22 opposite the plunger 30 in parallel relation to plate 34. Bar 38 preferably extends above the level of the upper margin of chute flanges 20 and 21. A tensioned coil spring 40 spans chute 10 having one end connected to upper margin 36 of plate 34 and the other end connected at the top of bar 38, causing plate 34 to facedly engage the outer face of chute flange 20 and to urge plunger 30 to project into and at least partly across the chute passageway 23 as shown in FIG. 2.

Solenoid 28 is electrically connected in a circuit having a power source 42 and a control switch 44. Switch 44, as shown in FIG. 3, may be carried by the chute 10 adjacent its upper end and is normally urged to open position by a spring 47. Trip means 46 is deflected under the weight of a type casting sliding thereon to close switch 44 and energize the solenoid 28 to withdraw plunger 30 from passageway 23 of the chute 10.

In operation, as a casting is discharged from the type casting machine and passes over trip means 46, switch 44 is closed causing momentary energizing of solenoid 28 and withdrawal of plunger 30 from chute passageway 23, permitting any casting which has been detained by the plunger 30 to slide down chute 10. After a casting passes the trip means 46, it returns to normal open circuit position under the influence of spring 47, thereby deenergizing solenoid 28 and permitting plunger 30 to be returned to its passage-spanning position by spring 40. Plunger 30 is thus reinserted to span the passageway 23 before

the type casting which has left the trip means 46 reaches the plunger 30 so that it contacts plunger 30 and is detained thereby until plunger 30 is withdrawn in response to operation of the trip means 46 following discharge of another casting from the type casting machine.

FIG. 5 illustrates an alternative position of switch 44 relative to plunger 30. In this modification trip means 46 is located adjacently above-passage to plunger 30. In operation, upon discharge from the type casting machine, the casting proceeds down chute 10 until it contacts and is stopped or slowed by plunger 30 spanning passageway 23 of the chute 10. At the same time the casting deflects trip means 46, closing switch 44. Solenoid 28 is then energized causing the withdrawal of plunger 30 from passageway 23 and from contact with the detained casting. The casting then proceeds down chute 10, freeing trip means 46 and opening switch 44. Solenoid 28 is

then deenergized and plunger 30 reinserted into passageway 23 under the influence of spring 40 to await contact with the next casting.

The positioning of plunger 30 only a slight distance above conveyor 14 insures that the type casting cannot attain a high speed of travel down the lower part of the chute 10 including the delivery portion 19 of the bottom of the chute 10 projecting between the conveyor guides 16. The parts will be so positioned that a type casting will attain a speed of travel substantially equal to the speed of travel of the conveyor 14.

It will be understood that the invention is not to be limited to the details herein given but may be modified within the scope of the appended claims.

I claim:

1. In an apparatus for assembling printing type line castings discharged from a type casting machine, an inclined chute defining a passageway and having an upper end adapted to be connected to the discharge end of said type casting machine and a lower delivery end, conveyor means for receiving type castings from the delivery end of said chute and transporting said castings to an assembly table, retainer means carried by said chute and including a shiftable part projectable into said passageway, said retainer means positioned between said upper and lower chute ends and including biasing means normally urging said retainer means part into said passageway to engage a first of said castings and arrest its movement within said passageway, actuating means operatively connected to said retainer means for withdrawing said retainer means part from said passageway to release said first casting, a switch associated with said actuating means including operating means positioned within said passageway between said retainer means part and said upper chute end responsive during the passage of a second of said castings thereacross for momen-

tarily activating said actuating means to cause the withdrawal of aid retainer means part from said passageway and thereby release said first casting, the spacing between said retainer means part and said switch operating means being sufficient to allow said retainer means part to be urged back into said passageway by said retainer biasing means after said second casting crosses said switch operating means and before said second casting reaches said retainer means part.

2. In an apparatus for assembling printing type line castings discharged from a type casting machine, an inclined chute defining a passageway and having an upper end adapted to be connected to the discharge end of said type casting machine and a lower delivery end, conveyor means for receiving type castings from the delivery end of said chute and transporting said castings to an assembly table, retainer means carried by said chute and including a shiftable part projectable into said passageway, said retainer means positioned between said upper and lower chute ends and including biasing means normally urging said retainer means part into said passageway to engage one of said castings and retard its movement within said passageway, actuating means operatively connected to said retainer means for withdrawing said retainer means part from said passageway to release said casting, a switch associated with said actuating means including operating means positioned within said passageway adjacently above-passage of said retainer means part, said switch operating means responsive to the passage of said casting thereacross for activating said actuating means, said retainer means part and said switch operating means being so positioned longitudinally along said passageway and relative to each other that said casting first contacts said retainer means part before said switch operating means activates said actuating means.
